L. B. CAMPBELL

RADIATOR ORNAMENT

Filed Nov. 19, 1926

FIG. 1.

FIG. 4.

FIG. 5.

FIG. 2.

FIG. 3.

By *Lacy, Lacy*, Attorneys.

UNITED STATES PATENT OFFICE.

LAWRENCE BRYAN CAMPBELL, OF WASHINGTON, DISTRICT OF COLUMBIA.

RADIATOR ORNAMENT.

Application filed November 19, 1926. Serial No. 149,467.

The invention relates to an ornament for the cap of motor vehicle radiators, the primary intent being the provision of an article which is attractive, particularly when the vehicle is in motion, because of an animated effect produced by the flutter of a drapery, such as a metal fabric.

The invention supplies an ornament of the character aforesaid consisting of a figure, representative of the human form, poised upon a pedestal, with the upper portion inclined forwardly and the arms outstretched and rearwardly inclined and a drapery, preferably of metal fabric, attached to the hands and gathered about and connected to the neck, after the fashion of a cloak or mantle, and permitted to hang loose to flutter in the breeze and thereby produce an animated effect.

For a full understanding of the invention and the merits thereof reference is to be had to the subjoined description and the drawings hereto attached in which corresponding and like parts are designated by like reference characters.

Referring to the drawings:

Figure 1 is a front view of an ornament of the character hereinbefore stated embodying the invention, showing the same attached to the cap of a motor vehicle radiator.

Figure 2 is a side view of the ornament showing the drapery in hanging position, when not acted upon by a breeze.

Figure 3 is a view similar to Figure 2, showing the drapery extended, substantially as it will appear when acted upon by a breeze.

Figure 4 is a detail view showing a spring clip for attaching the drapery to the figure, and

Figure 5 is a detail view of a portion of a metal or chain fabric which is preferably employed as the draping means.

The numeral 1 designates the figure which, for the sake of illustration represents the human form, said figure being erect and poised upon a pedestal 2 and having the upper portion of the body inclined forwardly, and the arms outstretched and inclined rearwardly. To produce an aesthetic effect the figure is unclothed to disclose a well developed outline and graceful pose.

The drapery 3 consists of a fabric, such as an approximately square cloth, which is attached at its upper edge to the neck and hands of the figure, and which extends along

the arms and shoulders and over the back of the figure and hangs outstretched, as indicated most clearly in Figure 1. The fabric 3 is of a nature to assume graceful folds and is sufficiently weighted to insure its fluttering in a breeze. The fabric best suited for the purpose is of the nature employed in the manufacture of metal or chain mesh purses and hand bags, and is of a nature and finish to resist the action of the elements and climatic conditions. The drapery approximates a mantle or cloak and may be attached to the neck and wrists of the figure in any determinate way, it being preferred to utilize spring clips 4 which admit of the drapery being readily placed in position or removed as required. When the drapery is unaffected by a breeze it hangs about the figure, substantially as indicated in Figure 2 and when subjected to the action of a breeze from the front, it is extended, substantially as indicated in Figure 3. The drapery, when extended also flutters, thereby producing an animated effect calculated to attract the attention, which is further heightened by the pose and outline of the figure. A threaded stem 5 depends from the pedestal 2 and provides means for attaching the figure to the cap 6 of an automobile or other motor vehicle radiator.

While the figure illustrated is preferred, because of the graceful outline and pose, it is to be understood that within the purview of the invention a figure of any design and pose may be employed, so long as a mantling drapery is associated therewith to produce an animated effect in a breeze by a fluttering thereof. When the vehicle is moving slowly the drapery, by reason of its metallic nature, receives a tremulous and agitating movement which, in its association with the figure, produces an attractive and beautiful effect.

The metal or chain mesh fabric employed admits of the effect being heightened by variously coloring the same, the hues and colors blending to produce a resplendent and chameleon shimmer in the sun or other strong light.

Having thus described the invention, I claim:

1. An ornament of the character specified comprising an upright figure having arms outstretched and a weighted drapery consisting of flexible fabric formed of a multiplicity of interconnected metallic elements and suspended from the shoulders and arms and

adapted to hang loosely therefrom to be acted upon by a breeze to flutter therein and produce an animated effect.

2. An ornament of the character specified, comprising a human figure in upright position and having arms outstretched, a weighted drapery consisting of a chain mesh fabric provided with spring clips to engage about the neck and wrists of the figure to support the drapery which hangs loose from the shoulders and arms to be affected by a breeze in which it is adapted to flutter and produce an animated effect.
3. An ornament of the character specified comprising an upright figure having outstretched arms, a flexible fabric formed of

a multiplicity of interconnected metallic elements and adapted to hang loosely from the shoulders and arms of the figure to flutter in a breeze, and means for detachably connecting the fabric to the neck and outstretched members of the figure.

4. An ornament comprising a figure, and a weighted flexible drapery for the figure formed of a multiplicity of interconnected metallic elements, said drapery being suspended from the figure to be affected by a breeze and thereby caused to flutter and produce an animated effect.

In testimony whereof I affix my signature.

LAWRENCE BRYAN CAMPBELL. [L. S.]
